UNITED STATES PATENT OFFICE

150,036

DESIGN FOR A BOX

Sidney X. Shore, New York, N. Y.

Application June 17, 1946, Serial No. 130,764

Term of patent 14 years

(Cl. D58—12)

To all whom it may concern:

Be it known that I, Sidney X. Shore, a citizen of the United States, residing at New York, in the county of New York and State of New York, have invented a new, original, and ornamental Design for a Box, of which the following is a specification, reference being had to the accompanying drawings, forming part thereof.

Fig. 1 is a perspective view of a box in closed position, showing my new design;

Fig. 2 is a perspective view thereof in open position;

Fig. 3 is a front elevation of the closed box;

Fig. 4 is a side elevation thereof;

Fig. 5 is a rear elevation thereof; and

Fig. 6 is a sectional view along the line 6—6 in Figure 5.

I claim:

The ornamental design for a box, as shown.
SIDNEY X. SHORE.
